US0D1064073S

(12) **United States Design Patent** (10) Patent No.: **US D1,064,073 S**
(45) Date of Patent: ** Feb. 25, 2025

(54) **ELECTRONIC DISPLAY UNIT**

(71) Applicant: **Manufacturing Resources International, Inc.**, Alpharetta, GA (US)

(72) Inventors: **William Dunn**, Alpharetta, GA (US); **Mike Brown**, Cumming, GA (US)

(73) Assignee: **Manufacturing Resources International, Inc.**, Alpharetta, GA (US)

(**) Term: **15 Years**

(21) Appl. No.: **29/937,793**

(22) Filed: **Apr. 17, 2024**
